UNITED STATES PATENT OFFICE.

JOHN S. WHEELER, OF DUNSMUIR, CALIFORNIA.

PIPE-BENDING MACHINE.

1,206,742.

Specification of Letters Patent. Patented Nov. 28, 1916.

Application filed March 10, 1915. Serial No. 13,429.

To all whom it may concern:

Be it known that I, JOHN S. WHEELER, a citizen of the United States, residing at Dunsmuir, in the county of Siskiyou and State of California, have invented certain new and useful Improvements in Pipe-Bending Machines, of which the following is a specification.

The invention provides an appliance which admits of tubing being readily bent into any desired form without distorting the cross sectional outline thereof.

In the process of bending pipes or tubes, the same are often flattened because of unequal application of pressure. Moreover, the tube is frequently distorted because of weak places. The present invention provides a machine which may be readily adapted to the peculiar nature of the work in hand and which in operation will preserve the outline of the pipe in cross section throughout the bending process, the machine being adaptable to take care of any weak places that may develop in the pipe during the process of bending and which tend to cause the pipe to bulge or not conform to the shape of the form about which the pipe is bent.

A further purpose of the invention is the provision of a machine which admits of bending a pipe or tube in any direction or upon any desired curve depending upon the shape to be imparted thereto.

With these and other objects in view which will readily appear as the nature of the invention is better understood, the same consists in the improved construction and novel arrangement and combination of parts which will be hereinafter fully described and particularly claimed.

In the accompanying drawings has been illustrated a simple and preferred form of the invention, it being, however, understood that no limitation is necessarily made to the precise structural details therein exhibited, but that changes, alterations and modifications within the scope of the invention as claimed may be resorted to when desired.

Referring to the drawings, — Figure 1 is a top plan view of a pipe bending machine embodying the invention; Fig. 2 is a vertical longitudinal section on the line 2—2 of Fig. 1; Fig. 3 is a transverse section on the line 3—3 of Fig. 1; Fig. 4 is a top plan view of a portion of the machine showing a different adjustment of the pressure piece; Fig. 5 is a detail perspective view of the pressure piece

and adjunctive parts, and Fig. 6 is a detail perspective view of a supplemental pipe form.

Corresponding and like parts are referred to in the following description and indicated in all the views of the drawings by the same reference characters.

The machine comprises a base 1, which may be of any construction so as to form a substantial support for the working parts. Mounted upon the base 1 is the pipe or tube bending mechanism, the same comprising a pipe form, a pressure piece and a leverage mounting for the pressure piece. The pipe form may be of any construction and comprise one or more parts but it is preferred to have the same constructed of sections, thereby adapting the machine for different curves and sizes of pipes or tubes. As indicated most clearly in Figs. 1 and 2 the machine comprises an intermediate pipe form 2 and end pipe forms 3 and 4. Each of the pipe forms has its active portion curved as plainly indicated in Fig. 1 and when bending a pipe or tube the particular form corresponding with the curve to which the pipe is to be bent is selected. The active portion of the pipe form is that about which the pipe or tube is bent and such active portion is formed with an approximate half round groove corresponding to the size, or diameter, of the pipe so as to form a snug seat for the pipe. The pipe forms are supported a distance from the base 1 and are connected thereto by means of bolts or like fastenings 5. Spacing sleeves 6 are slipped upon the bolts or fastenings 5 and come between the base 1 and pipe forms. Plates 7 are placed upon the several pipe forms and overlap the joints formed between them and are retained in place by means of the fastenings 5. These plates serve as connecting means to retain the pipe forms in place. The middle pipe form 2 is of circular outline and has a half round groove 8 in its edge conforming to the diameter of the pipe or tube to be bent. When the machine consists of a single pipe form, as 2, it is to be understood that it is adapted for one size of pipe or tube only.

The pipe forms 3 and 4 are supplementary and are provided in different sizes, thereby adapting the machine for general use for bending pipes or tubes of different sizes and in varying curves. The pipe forms 3 and 4 are similar in construction but different in size and are adapted to be replaced by other

forms of different size when adapting the machine to any special or particular work. When the pipe forms 3 and 4 are in place their active portions face outward in opposite directions and are formed with half round grooves 9. The portions of the supplementary pipe forms 3 and 4 placed against the intermediate pipe form 2 are concave to form a close joint with the part 2. The concave ends or portions of the supplementary pipe forms have ribs 10 which are adapted to fit within the half round groove 8 of the pipe form 2. This interfitting of the meeting portions of the pipe forms insures an alinement of the parts and prevents possible displacement when the machine is in operation.

It is to be understood that the pipe forms are preferably constructed of metal so as to withstand the wear and tear incident to the nature of the work for which the machine is designed.

The pressure piece adapted to coöperate with the pipe form is indicated at 11 and is approximately of half round outline, one edge being straight and formed with a half round groove 12 which corresponds with the half round groove of the pipe form with which the pressure piece is adapted to coöperate. It is to be understood that a pressure piece is provided for each pipe form so that the matching half round grooves will correspond with the diameter of the pipe or tube to be bent. The pressure piece 11 is preferably of metal. A clevis 13 forms part of the leverage mounting of the pressure piece. This clevis is substantially of U-form and is disposed with its longitudinal members embracing the upper and lower sides of the pipe form and pivoted thereto by means of a pin 14. The longitudinal members of the clevis 13 are formed with a plurality of openings 15, the openings in the upper member corresponding with the openings in the lower member. A lever 16 is adjustably connected with the clevis 13 by means of a pin 17 which passes through an opening formed in the lever 16 and through selected openings 15 in the upper and lower members of the clevis 13. A clip 18 embraces opposite sides of the lever 16 and pressure piece 11 and is attached to each by means of pins 19 and 20. The pin 20 is disposed concentric with the circle upon which the curved edge of the pressure piece 11 is formed, hence the pressure piece is adapted to turn about the pivot fastening 20 and at the same time have its curved edge remain in contact with the lever 16. As a result of this arrangement the straight edge of the pressure piece may remain in contact with the pipe or tube throughout its extent during the entire bending operation, thereby distributing the pressure upon the pipe or tube so as to prevent disturbing

the outline of the pipe or tube during the bending operation. The straight edge of the presser piece may be turned to various angles relative to the lever 16 so as to readily engage the work without requiring the lever 75 to be disconnected, and the pressure of the lever is exerted through its side and not through its end so that it is most effectually applied. Straps 21 connect the pressure piece 11 with the clevis 13. The straps 21 are disposed so as to embrace opposite sides of the pressure piece and are pivotally connected thereto by means of a pin 22 and to the clevis 13 by means of a pin 23. The pin 23 may be shifted to any selected openings 15 of the clevis 13 depending upon the position of the lever 16. The lever 16 is adapted to have a handle 24 fitted thereto for increasing the leverage as required. Circular supports 25 and 26 are disposed at opposite ends of the pipe form and are adapted to receive and support the pressure piece and the leverage mechanism coöperating therewith. The support 25 consists of a single bar whereas the support 26 is shown as comprising two bars. The curved supports are in a plane parallel with a plane passing through the pipe form so as to engage the pressure piece and lever and support the same throughout the bending operation.

The pipe or tube to be bent is indicated at 27 and is retained in place by means of a suitable clamp which may comprise any number of elements. The pipe form constitutes one jaw of the pipe clamping means and the other jaw is indicated at 28 and is movable. The movable jaw 28 is hinged at its lower end, as indicated at 29, and is formed intermediate its ends with a crimp 195 or depression 30 corresponding with the diameter of the pipe and arranged to come opposite the half round groove of the pipe form. A bracket 31 is secured to the pipe form and is adapted to coöperate with the movable jaw 28 and a clamp screw 32 so as to draw the jaw 28 toward the pipe form and clamp the pipe or tube to be bent. The jaw 28 is hingedly connected to the base 1 and may be replaced, if desired, by a jaw having a depression 30 of a different size according to the diameter of the pipe to be gripped. It is to be understood that the pipe clamping means may comprise any number of gripping elements so as to secure the pipe and prevent any possible movement thereof during the bending operation.

The pipe forms have central openings 33 to receive the pivot pin 14 of the clevis 13 and other openings 34 near their active edges 125 to receive the pivot pin 11 when the pressure mechanism is required to be moved outward as indicated in Fig. 4. In the ordinary use of the machine the pressure mechanism is pivotally connected to the pipe form 130

at the central point 33 so that the pressure piece may travel about the active edge of the pipe form and remain at a uniform distance therefrom with the result that the pipe 5 is confined between the grooved edges of the pipe form and pressure piece, thereby preventing any distortion of the pipe during the bending operation. It frequently happens that the pipe or tube develops a weak 10 place and as a consequence tends to bulge or spring away from the pipe form during the bending operation. In this event the clevis 13 is shifted outward and the pivot bolt 14 fitted in one of the openings 34, the 15 presser piece 11 and its connections being shifted inwardly along the clevis to the position indicated in Fig. 4. The clevis being thus mounted eccentrically to the curved edge of the form and the radial length of 20 the path of movement of the clevis being lessened, the presser piece will not be capable of swinging entirely around the end of the form, but will tend to swing inwardly against said end so that the material being 25 bent will be more quickly forced directly against the form. As only a short length of the pipe or rod can thus be bent at one step in the operation, with the parts adjusted as in Fig. 4, distortion at the weak 30 spot is avoided, and it is to be understood that the pivot 14 may be shifted successively from one to another of the openings 34 until the weak place in the pipe has been properly 35 bent the pressure mechanism is returned to its normal position, that is, with the pivot pin 14 in the central opening 33 of the pipe form, as indicated in Fig. 1. The supplementary pipe forms are of different sizes, 40 that is, diameters and are formed with grooves or pipe seats 9 of different sizes. As a consequence the machine may be readily adapted for bending pipes or tubes of different diameters and upon grooves varying 45 in diameter.

Having thus described the invention, what is claimed as new is:—

1. In a pipe-bending machine, the combination of a pipe form, a clevis pivoted to the pipe form, a lever pivoted to and extending laterally from the clevis in the plane of the pipe form, a presser piece disposed between and in the same plane with the lever and the pipe form, a clip connecting the lever 50 and the presser piece, and straps connecting the presser piece and the clevis.
2. In a pipe-bending machine, the combination of a pipe form having a plurality of pivot openings, a clevis having a longitudinal series of openings, a shiftable pivot 60 carried by the clevis and insertible in any one of the pivot openings in the pipe form, a lever extending laterally from the clevis, a pivot inserted through the lever and one of the openings in the clevis, a presser piece 65 between the lever and the pipe form and co-operating with the pipe form, a clip connecting the presser piece with the lever, and straps connecting the presser piece with the clevis. 70
3. In a pipe-bending machine, the combination of a pipe form having an arcuate pipe-engaging edge, a clevis pivoted thereto, a lever extending laterally from the clevis in the plane of the pipe form, a presser piece 75 having a straight edge co-operating with the pipe form and an arcuate edge bearing against the side of the lever, a clip pivoted to the presser piece and connecting the same with the lever, and straps pivoted to the 80 clevis and to the presser piece near one end of the straight edge thereof.
4. A pipe bending machine comprising a pipe form, a clevis pivotally connected with the pipe form, a lever extending laterally 85 from the clevis and having a constant movement relative thereto, a presser piece arranged to bear against the side of said lever between the ends of the same and co-operate with the pipe form, connections between the 90 presser piece and the lever, and other connections between the presser piece and the clevis, said last-mentioned connections being entirely free of the lever.
5. A pipe bending machine comprising a 95 pipe form, a clevis having a shiftable and pivotal connection with the pipe form, a lever adjustably pivoted to and extending laterally from the clevis, a presser piece disposed between the lever and the pipe form 100 and bearing against the side of the lever between the ends thereof, connections between the presser piece and the lever, and other connections between the presser piece and the clevis, said last-mentioned connections being 105 free of the lever.

In testimony whereof I affix my signature in presence of two witnesses.
